United States Patent Office.

F. W. BROCKSIEPER, OF NEW HAVEN, CONNECTICUT, ASSIGNOR TO SARGENT AND COMPANY, OF SAME PLACE.

Design No. 3,033, dated May 12, 1868.

DESIGN FOR A CARD-RECEIVER.

The Schedule referred to in these Letters Patent and making part of the same.

TO ALL WHOM IT MAY CONCERN:

Be it known that I, F. W. BROCKSIEPER, of New Haven, in the county of New Haven, and State of Connecticut, have invented a new Design for a Card-Receiver; and I do hereby declare the following, when taken in connection with the accompanying drawing, to be a full, clear, and exact description of the same, and which said drawing constitutes part of this specification, and represents a perspective view.

This invention relates to a design for a cast-metal receptacle for cards, and like purposes, in imitation of carved wood, and represents an oak-leaf, the edges of which are turned up, so as to give it a dish or concave form upon the upper surface, the stem of the leaf appearing as a handle, all as fully shown in the accompanying illustration.

Having described my invention, what I claim as new, and desire to secure by Letters Patent, is—
The design for a card-receiver, as herein described and illustrated.

F. W. BROCKSIEPER.
